UNITED STATES PATENT OFFICE.

JOHN LINES, OF WATERBURY, CONNECTICUT, ASSIGNOR TO THE SCOVILL MANUFACTURING COMPANY, OF SAME PLACE.

DESIGN FOR A TIRE-VALVE CAP.

SPECIFICATION forming part of Design No. 28,584, dated May 10, 1898.

Application filed October 18, 1897. Serial No. 655,639. Term of patent 7 years.

To all whom it may concern:

Be it known that I, JOHN LINES, of Waterbury, in the county of New Haven and State of Connecticut, have invented a new Design 5 for a Tire-Valve Cap, (Case A;) and I do hereby declare the following, when taken in connection with the accompanying drawings and the letters of reference marked thereon, to be a full, clear, and exact description of the same, 10 and which said drawings constitute part of this specification, and represent, in—

Figure 1, a side view of a cap embodying my design; Fig. 2, a side view at right angles to that shown in Fig. 1.

15 This invention relates to a design for tire-valve caps; and the design consists in the form of the cap, as hereinafter described, and shown in the accompanying illustration.

As herein shown, the tire-valve cap of my

design is characterized by having the body B 20 surrounded by an annular knurled band A, extending around the body below its upper end, by having its upper end C flat, and by having a round post F projecting upward from the center of the upper end C, which post is 25 cut away on opposite sides of its center at its outer end to form a transverse edge G, all as shown in the accompanying illustration.

I claim—

The design for a tire-valve cap as herein 30 shown and described.

In testimony whereof I have signed this specification in the presence of two subscribing witnesses.

JOHN LINES.
